UNITED STATES PATENT OFFICE.

WILLIAM H. BALES, OF FARMLAND, INDIANA.

CEMENT VAULT.

1,023,118.

Specification of Letters Patent. Patented Apr. 16, 1912.

Application filed August 21, 1911. Serial No. 645,072.

To all whom it may concern:

Be it known that I, WILLIAM H. BALES, a citizen of the United States, residing at Farmland, in the county of Randolph and 5 State of Indiana, have invented a new and useful Cement Vault, of which the following is a specification.

It is the object of the present invention to provide a burial case, the sides and ends 10 of which are connected in a novel manner, by means of a dove-tailed construction, whereby the sides and the ends will be drawn together automatically, to secure the corners of the case.

15 A further object of the invention is to provide novel means for preventing water from leaking through the lid of the case.

A further object of the invention is to provide a burial case which may be lowered 20 into the grave piece-meal, the construction being such that the burial case may be assembled readily in the grave.

With the foregoing and other objects in view which will appear as the description 25 proceeds, the invention resides in the combination and arrangement of parts and in the details of construction hereinafter described and claimed, it being understood that changes in the precise embodiment of 30 invention herein disclosed can be made within the scope of what is claimed without departing from the spirit of the invention.

In the accompanying drawings,—Figure 1 shows the invention in sectional side elevation; Fig. 2 is an end elevation; Fig. 3 is a vertical transverse section upon the line A—B of Fig. 1; Fig. 4 is a perspective showing the sides and the ends of the burial case in spaced relation; and Fig. 5 is a perspective of the bottom of the burial case, showing the constituent elements of the bottom in spaced relation.

Considered generally, the burial case herein disclosed comprises a top 1, resting upon 45 sides 2, the sides 2 being interengaged with ends 3, the ends 3, of course, coöperating with the sides 2 in supporting the top 1, the ends 2 and the sides 3 being supported upon the bottom 4.

50 The bottom 4 (see Fig. 5) is transversely divided to form sections 5. The bottom 4, considered as an entity, is provided with a central upstanding rib 6, about which the sides 2 and the ends 3 fit. The rib 6 serves 55 to define a flange 7 about the periphery of the bottom 4, and upon this flange 7 the

sides 2 and the ends 3 rest. Upon each of the sections 5 of the bottom 4 there is an upstanding lug 8, adapted to support the coffin in spaced relation with respect to the bottom 4. The sections 5 of the bottom 4 are provided along their meeting edges with overlapping lips 9, preferably, although not necessarily, of rectangular construction.

The top 1 consists of sections 33, similar 60 in extent to the sections 5 of the bottom 4. These sections 33 are equipped at their ends with overhanging lips 10. The abutting faces 11 of the lips 10 are diagonally disposed with respect to the plane of the top 70 1, the construction being such that in one of the sections 33 there is fashioned a groove 12, extended the full width of the top 1. Any moisture finding its way into the groove 12, will be conducted transversely of 75 the burial case, and will be delivered beyond the contour of the case, instead of trickling down upon the coffin. The interior of the case is maintained, further, in a dry condition, by reason of the fact that the upper 80 edges of the sides 2 and of the ends 3 will slant downwardly and outwardly, as shown at 14. Into the angles defined by the slant edges 14 and by the lower face of the top 1, cement 15 may be inserted; and, indeed, it 85 will be understood without further reference, that all of the interstices in the case may be cemented, if desired.

Four duplicate structures are provided, 90 each of which serves to unite one end of one of the sides 2 with one end of the end members 3. But one of these structures will be described. The side 2 is cut away as shown at 16, upon its inner face 17, to define a primary shoulder 18 and a rectangularly 95 disposed secondary shoulder 19, there being an inwardly projecting lower lug 20 located adjacent the bottom of the side 2, in the angle defined by the primary shoulder 18 and the secondary shoulder 19. The upper 100 face 21 of the lug 20 slants downwardly and outwardly, the secondary shoulder 19 terminating as shown at 22, short of the upper edge 23 of the side 2. The secondary shoulder 19 is provided with a downwardly and 105 outwardly slanting upper face 24, the face 24 extending throughout a portion only of the length of the shoulder, to define an upper lug 25. The end 3 is provided in its end wall 26 with a lower notch 27, and with an upper notch 28, the lower faces 29 of both 110 of which, slant inwardly and upwardly, the

lower notch 27 defining a lug 30, adapted to engage with the lower lug 20 of the side 2, and the upper notch 28 defining a lug 31 adapted to engage over the upper edge of 5 the secondary shoulder 19, behind the up-standing lug 25. The lug 31 is equipped with a recess 32, adapted to receive the upper lug 25 of the side 2. It will be seen that, owing to the foregoing construction, 10 the side and the end of the burial case will be held securely together at their points of juncture.

The burial case may be placed, piece by piece, within the grave, by one person, and 15 may be assembled in the grave, thereby obviating the necessity of employing cumbersome hoisting mechanism, or the necessity for calling into requisition, the services of more than one person.

20 Having thus described the invention what is claimed is:—

A burial case including a side cut away upon its inner face to define a primary shoulder and a rectangularly disposed secondary shoulder, there being an inwardly projecting lower lug located adjacent the bottom of the side, in the angle defined by 25

the primary and secondary shoulders, the upper face of the lug slanting downwardly and outwardly, the secondary shoulder terminating short of the upper face of the side, and having its upper face slanted downwardly and outwardly for a portion of its length only, to define an upper lug; and an end adapted to abut laterally against the 30 primary shoulder and to abut terminally against the secondary shoulder, the end being provided in its end wall with a lower notch and with an upper notch, the lower faces of both of which slant inwardly and 40 upwardly, the lower notch defining a lug adapted to engage the lower lug of the side, and the upper notch defining a lug adapted to engage over the upper edge of the secondary shoulder behind the upper lug, the 45 last named lug of the end having a recess to receive the upper lug of the side.

In testimony that I claim the foregoing as my own, I have hereto affixed my signature in the presence of two witnesses.

WILLIAM H. BALES.
